CLAIM

The ornamental design for an articulating arm, as shown and described.

DESCRIPTION

FIG. 1 is an isometric right-side view of an articulating arm; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is an isometric right-side view of the articulating arm of FIG. 1 shown in a lowered position. The broken lines in FIGS. 1–8 illustrate portions of the articulating arm that form no part of the claimed design.
